INSULATED DOOR

Stuart F. King, Mount Clemens, Mich., assignor to Philco Corporation, Philadelphia, Pa., a corporation of Pennsylvania

Application April 12, 1949, Serial No. 87,059

4 Claims. (Cl. 126—200)

1

The present invention relates to an insulated door and more particularly to an insulated door provided with an observation window.

The insulated door of the present invention is particularly adapted for use with heating apparatus, for example, as an oven door for a cooking range or stove. An observation window is secured within the insulated door construction by engagement of the door with marginal portions of the window to permit observation through the window while preventing interference of the door construction with the view therethrough.

In general, the door of the present invention comprises cooperating front and rear panels defining a hollow door interior therebetween, and an additional door stiffener plate disposed within the door interior is secured to one of the panels. The other door panel, in cooperation with the stiffener plate, defines a space within the door which is filled with suitable insulation, as for example a conventional insulation batt.

The door observation window, preferably in the form of a pair of convex glass plates joined at their peripheries to define a hollow interior, is engaged about its outer periphery by a flange formed in the stiffener plate. The inner and outer door panels are dished inwardly toward the interior of the door to engage opposing peripheral surface portions of the window to maintain the same against longitudinal movement. Thus, the stiffener plate and the front and rear door panels cooperate to maintain the window in position therebetween.

The hollow interior of the glass window affords insulation for the window to reduce heat transfer therethrough, while the insulation between the stiffener plate and one door panel also hinders heat transfer through the door. In addition, the front and rear door panels are spaced from one another so that they are out of contact, thus further reducing heat transfer through the door.

In order to maintain the spacing between the front and rear door panels, the panels are secured together by means of a plurality of additional fastening members, certain of these fastening members being secured to the front door panel and certain others being secured to the rear door panel. Suitable fastening means, as, for example, conventional screws, are employed to secure these fastening members together to maintain the front and rear door panels in assembled relation with the window being securely clamped therebetween.

It is, therefore, an important object of the present invention to provide an improved insulated door

2

Another important object of the present invention is to provide an improved insulated door having an observation port or window therein.

Still another important object of the present invention is to provide an improved insulated door in which front and rear door panels are separated by insulating means and also by a marginal air gap to substantially reduce heat transfer through the door.

It is a further important object of the present invention to provide an improved insulated door including spaced front and rear door panels and a stiffener plate disposed therebetween to maintain a glass window having a hollow interior against movement in one direction with the cooperating door panels preventing movement in another direction.

Other and further important objects of this invention will be apparent from the disclosures in the specification and the accompanying drawings.

On the drawings:

Figure 1 is a rear elevational view of an insulated door of the present invention;

Figure 2 is a sectional view taken along the plane II—II of Figure 1; and

Figure 3 is a fragmentary, sectional view taken along the plane III—III of Figure 1.

As shown on the drawings:

In Figure 1, reference numeral 10 refers generally to an insulated door of the present invention defined by an inner door panel 11 and an outer door panel 12.

As shown in Figure 2, the inner door panel 11 is provided with an outer marginal flange 13 which is turned inwardly toward the interior of the door 10 and an inner offset portion 14 adjacent the flange 13. The inner margin of the rear panel 11 is defined by an inturned, generally cylindrical flange 15 having an inner annular edge 15a for a purpose to be hereinafter more fully described.

The outer door panel 12 is provided with an outer marginal flange 16 of substantially greater length than the flange 13 of the inner door panel 11 and adapted to overlie flange 13 as shown in Figure 2. The inner margin of the outer door panel 16 is defined by an inner, generally cylindrical flange 17 of substantially the same radius of curvature as the flange 15 of the inner panel 11 and having an annular inner edge 17a facing edge 15a and spaced therefrom.

The panels 11 and 12 are secured together by suitable means as shown in Figure 3 in which it will be seen that each corner of the outer door panel is provided with a substantially U-shaped,

centrally apertured bracket 18 having outwardly extending legs 19 secured to the panel 12 intermediate the flanges 16 and 17 by suitable means, as by spot welding. Each corner of the inner door panel 11 is also provided with a centrally apertured bracket 20 of generally triangular outline (Figure 1) secured to adjacent corner marginal portions 14 of the panel 11 by spot welding, as at 21. The inner panel 11 is also provided with spaced inwardly dished portions 22 which are apertured for registry with the apertures in the brackets 18 and 20 to receive a screw 23 therethrough. The screw 23 is threadedly received by the brackets 18 and 20 and serves to draw the brackets together, thus maintaining the inner and outer panels 11 and 12 in spaced relation.

It is to be noted from Figures 2 and 3 that the panels 11 and 12 are so spaced that a slight marginal spacing 24 results between the flanges 16 and 13. This marginal spacing 24, by preventing surface contact between the panels, materially aids in reducing heat transfer between the same.

An interior door stiffener plate 25 is positioned between the panels 11 and 12 and is secured to the inner surface of the inner panel 11 by suitable means, as by spot welding, as at 29a (Figure 1). The stiffener plate 25 is generally diamond-shaped in outline and is secured to opposing marginal portions 14 of the inner panel 11. The stiffener plate is provided with an inner, generally cylindrical flange 26 extending into closely spaced relation to panel 12, the flange 26 being substantially larger in diameter than the flanges 15 and 17 of the members 11 and 12, respectively.

An insulation batt 27 is disposed in the interior of the door 10, the batt being partially confined between the stiffener plate 25 and the outer wall 12 and partially confined between the inner and outer panels 11 and 12 at the corners of the door where the stiffener plate 25 is cut away.

An insulated window construction 28 of generally circular contour is provided in the door 10 to permit observation therethrough, the window construction 28 comprising essentially a pair of circular, convex plates 29 and 30 joined at their peripheral margins to define a hollow evacuated interior 31. The window construction 28, as best shown in Figure 2, is confined within the door 10 by peripheral contact with the flange 26 of the stiffener plate 25, preventing vertical movement of the window 28, and the cooperating opposed flange edges 15a and 17a of the panels 11 and 12, which contact the plates 29 and 30, respectively, adjacent their marginal edges, to prevent longitudinal movement of the window 28.

The outer door panel 12 carries a handle 32 secured thereto by suitable means as by screws 33 threadedly retained by the handle and extending through the outer panel 12. The stiffener plate 25 carries in each lower corner portion a door mounting bracket 34 secured thereto by suitable means, as by spot welding.

The advantages residing in the improved insulated door construction of the present invention will be evident to those skilled in the art. The positioning of the observation port or window 28 within the door construction by the co-operation of the inner and outer panels 11 and 12, respectively, and the stiffener plate 25 prevents both the lateral and vertical movements of the window. Also, the marginal air gap 24 between the inner and outer panels effectively reduces heat transfer through the door construction.

It will, of course, be understood that various details of construction may be varied through a wide range without departing from the principles of this invention, and it is, therefore, not the purpose to limit the patent granted hereon otherwise than necessitated by the scope of the appended claims.

I claim as my invention:

1. An insulating door construction comprising a pair of cooperating door panels secured together to define an air space therebetween, said panels having outer marginal flanges spaced to provide an outer marginal air gap therebetween and inner marginal flanges turned toward each other defining aligned window openings, said inner flanges having spaced terminal edges, an additional plate secured to one of said panels and having an turned flange spaced outwardly from the spaced inner flange edges of said panels, and a unitary window between said panels rigidly secured in position by contact of its outer edge portions about the complete periphery of said window with the flange of said additional plate and by contact of marginal window portions adjacent to and coextensive with said window edge portions with the opposed flange edges of said panels.

2. An insulated door comprising an inner door panel having an inwardly extending bracket, an outer door panel also having an inwardly extending bracket for abutment with said first-mentioned bracket, means carried by one of said door panels and extending through said brackets to maintain the same in abutment to retain said panels in spaced apart relation, facing outer marginal flanges on said panels with the flange of said outer door panel overlying the outer flange of the inner door panel in spaced relation thereto to provide an insulating air gap, said panels having circular openings defined by facing inner marginal annular flanges having spaced apart terminal annular edges, an interior stiffening plate secured to one of said panels and having an inner annular flange concentric with and spaced radially outward from the inner flanges of said panels, and a circular insulating window construction having its outer periphery abutting the flange of said stiffener plate and having exterior marginal portions radially inward from said outer periphery in contact with said facing terminal annular edges of said inner marginal annular flanges, whereby the cooperating flanges of said panels and said stiffener plate prevent both lateral and vertical movement of said window.

3. An insulated door comprising an inner door panel having an inwardly extending bracket, an outer door panel also having an inwardly extending bracket for abutment with said first-mentioned bracket, means carried by one of said door panels and extending through said brackets to maintain the same in abutment to retain said panels in spaced apart relation, said panels having aligned openings defined by facing inner marginal flanges having spaced apart terminal edges, an interior stiffening plate secured to one of said panels and having an inner flange generally parallel with and spaced outwardly from the inner flanges of said panels, and a unitary insulating window construction having its outer periphery abutting the flange of said stiffener plate and having exterior marginal portions inwardly from said outer periphery in contact with said facing terminal edges of said inner mar-

ginal flanges, whereby the cooperating flanges of said panels and said stiffener plate prevent both lateral and vertical movement of said window.

4. An insulated door construction comprising a generally rectangular outer door panel and a generally rectangular inner door panel, overlapping marginal flanges on said door panels, a stiffener plate interposed between said panels and rigidly secured to one of said panels closely adjacent to the central portion of the marginal flange of said one panel, an inwardly extending bracket secured at each corner of said inner door panel, an inwardly extending bracket at each corner of said outer door panel for abutment with said first-mentioned bracket, means carried by one of said door panels and extending through said brackets to maintain the same in abutment to retain said panels in spaced apart relation without interference of said stiffener plate, said panels having inner marginal flanges inturned toward each other defining aligned window openings, said inner flanges having spaced aligned terminal edges, an additional plate secured to one of said panels and having an inturned flange spaced outwardly from the spaced flange edges of said panels, and a unitary window between

said panels rigidly secured in position by contact of its outer edge portions about the complete periphery of said window with the flange of said additional plate and by contact of marginal window portions adjacent to and coextensive with said window edge portions with the opposed flange edges of said panels.
